BRASSIÈRE AND BREAST PAD

Lester H. Loeffel, West Haven, Conn., assignor to
 The Berger Brothers Company, New Haven,
 Conn., a corporation of Connecticut

Application June 7, 1940, Serial No. 339,243

1 Claim. (Cl. 2—267)

This invention relates to breast pads and to brassières so constructed that the breast pads according to my invention may be worn therewith and readily detached therefrom, so that the garment may be cleaned.

In certain instances it is desired to wear breast pads such as in the case of a person who may have had a breast removed or in case of a person whose breasts are too flat for the accepted style. It quite often occurs that in the case of a breast operation one only of the breasts is removed, and in such case it will only be necessary to wear one breast pad. It is desirable in such an event, that the brassière be so constructed that without alteration it may be used with a single breast pad and the breast pad so formed that it will have the same appearance as the remaining natural breast.

In the formation of a breast pad it is desirable that it be made of soft and compressible material and that it be made of the proper shape to simulate the human breast. Also, it is advantageous for the face of the pad worn next to the body to be concave or hollow so that it may, if desired, be worn over and receive in the concavity the natural breast, if it is used as a supplement to a breast which is too flat.

One object of the present invention is the provision of a new and improved body or breast pad which may be made to suit any part of the individual figure and any amount of fullness be readily imparted to the pad.

A still further object of the invention is the provision of a new and improved breast pad which may be made of a sheet of relatively soft and pliable material, which may be cut and formed to simulate a breast of the desired size, and which, when so formed, will be concavo-convex in shape and will tend to retain its normal shape and return to shape when distorted.

A further object of the invention is the provision of a brassière so constructed that a breast pad made according to my invention may be removably secured to the brassière so that it may readily be detached in order that the garment may be cleaned.

A still further object of the invention is the provision of a brassière having breast pockets formed therein, which pockets are designed to removably receive and retain out of contact with the body of the wearer one or more breast pads, depending upon whether the wearer desires to use the pads upon both sides or upon one side only.

To these and other ends the invention consists

in the novel features and combination of parts to be hereinafter described and claimed.

In the accompanying drawing:

Fig. 1 is an inside elevational view of a brassière embodying my invention;

Fig. 2 is a sectional view through one of the breast pockets of the brassière, taken on line 2—2 of Fig. 1;

Fig. 3 shows one of the pockets removed from the brassière;

Fig. 4 is a sectional view of the pocket on line 4—4 of Fig. 3;

Fig. 5 is a front elevational view of a completed breast pad embodying my invention, and

Fig. 6 is a view of the blank from which the pad is made.

To illustrate a preferred embodiment of my invention, I have shown a brassière 10 which may be of the usual form except for the front section 11 thereof, which section is provided with breast pockets of novel form. It will be understood that the brassière is provided with the proper amount of fullness at the pocket portion of the garment, whereby it will be able to receive the breast pads described hereinafter. The breast pockets are shown, for example, at 12 in the garment and the particular construction thereof will be apparent from Figs. 3 and 4.

As shown in the latter figures, the pocket comprises a front wall 13 which may be the front wall of the brassière at this point or may be the front wall of a separate pocket sewed into the brassière. As shown, the wall 13 is the front ply of the garment. The front wall 13 is provided with fullness as shown in Fig. 4 to provide a pocket, the rear face of which is closed by flaps 14, 15 and 16, though I do not wish to be limited to the precise number of flaps disclosed.

It will be noted that each of these flaps is secured at the outer edges to the periphery of the wall 13 of the pocket, as shown, for example, at 17, 18 and 19, the outer edges of the flaps together corresponding to the outer edge of the pocket wall 13. The inner edge of each of the flaps 20, 21 and 22 is left free of the wall 13, as clearly shown in Fig. 4, and it will be seen that these edges overlap to a considerable extent and are also rounded or arc-shaped in form, whereby they may be nested into the concavity or pocket formed by the wall 13, or may be drawn or may stand forwardly of this wall depending upon the thickness of the breast pad to be used in the pocket, as will be explained hereinafter, and also depending upon the size of the breast of the person wearing the garment.

It will be apparent that these flaps, having their inner ends unsecured as described above, may be separated and pulled out from the pocket so that the breast pad may be readily inserted therein and removed therefrom. It will also be understood, however, that the flaps are always of such size and configuration that when in closed position, as shown in Figs. 3 and 4, they will overlap at all times so as to protect the pad from contact with the body. The use of a plurality of flaps having arcuate free edges so that the flaps may swing in or out toward or from the wall 13, provides for the fitting of the garment to flat or slightly curved breasts as well as for the proper fit of the garment when it is worn by one whose breast has been removed. Moreover, it will be understood that if desired where one breast has been removed, for example, a breast pad may be inserted in one of the brassière pockets only, the pad in such case being so made as to be of substantially the same size as the remaining breast. In case of flat or slightly curved breasts which are desired to be supplemented, it will be understood that the breast will project into the pocket and the formation of the flaps as described permits it to be worn over breasts of varying fullness.

In Figs. 2, 5 and 6 of the drawing I have shown a novel form of breast pad adapted to be inserted in the pocket of the brassière above described. As shown in Fig. 6, the pad may be made of a piece of sheet material 25, the edges of which are cut to the desired shape and which sheet of material is provided with cut-out portions or darts 26 and 27. When the edges of the darts are brought together, as shown in Fig. 5 along the lines 28 and 29, it will be seen that the sheet of material 25 will be formed into a concavo-convex shape. Varying degrees of fullness may be imparted to the pad thus formed by the size of the darts so that the pad may readily be formed to suit the individual for which it is being made.

As shown in Fig. 2, the edges of the blank or sheet of material are beveled or cut at an oblique angle to the original plane of the sheet, so that when the pad is formed as a concavo-convex body, these edges will lie in substantially the same plane, that is, the plane at the concave side of the pad, and will lie flatly against the

body of the wearer notwithstanding the substantial thickness of the material.

I prefer to use a sheet of material which has a considerable body or thickness and which will be light, soft and porous. I have found that sponge or foam rubber is desirable for this purpose on account of its softness and porosity and on account of the fact that it tends to assume its original shape when distorted. However, other material having similar characteristics may be used, if desired. The material may be approximately one-half inch in thickness and will be extremely light and at the same time will have sufficient body to hold its shape.

15 As shown in Fig. 2 of the drawing, the pads when made may be slipped into the pockets 12 by pulling outwardly the free edges of the flaps 14, 15 and 16, and placing the pad thereunder with its convex side toward the front of the garment. As shown in Fig. 2, the flaps of the breast pocket may swing inwardly against the surface of the pad if pressed therein by the breast of the wearer of the garment. However, if the garment is worn by one whose breast has 20 been removed the pad will retain its shape in a satisfactory manner without any inner support in addition to that given at the edges of the pocket by the flaps themselves.

30 While I have shown and described a preferred embodiment of my invention, it will be understood that it is not to be limited to all of the details shown, but is capable of modification and variation within the spirit of the invention and within the scope of the appended claim.

35 What I claim is:

A pocket or casing for a body or breast pad of concavo-convex form, said pocket being permanently closed at the front face thereof by a wall of rounded contour to fit snugly over the convex front face of the pad, and the rear face of the pocket comprising a plurality of flaps, each of said flaps being secured at its outer edges to the periphery of the front wall and having an edge of arcuate shape extending freely across the pocket, said free edges overlapping to close the pocket but being separable to permit the insertion of a breast pad therein, and said flaps having sufficient fullness to swing inwardly to positions adjacent the front wall of the pocket.
